UNITED STATES PATENT OFFICE.

GEORGE W. CURTIS, OF NEW BRITAIN, CONNECTICUT.

WINDOW-SHELF FOR PLANTS.

SPECIFICATION forming part of Letters Patent No. 783,622, dated February 28, 1905.

Application filed June 11, 1902. Serial No. 111,138.

To all whom it may concern:

Be it known that I, GEORGE W. CURTIS, a citizen of the United States, residing at New Britain, in the county of Hartford and State 5 of Connecticut, have invented certain new and useful Improvements in Window-Shelves for Plants, of which the following is a specification.

My invention relates to improvements in 10 window-shelves for plants; and the objects of my improvement are simplicity and economy in construction and convenience and efficiency in use and in particular to adapt the shelves for use on wide or narrow windows, as occasion 15 may require.

In the accompanying drawings, Figure 1 is a front elevation of my shelves as applied to 20 a window. Fig. 2 is a side elevation of the same with small portions broken out to show other parts. Fig. 3 is an enlarged detail section of a portion of my shelf on the line $x-x$ of Fig. 2. Fig. 4 is a transverse section of 25 one of the trays on a larger scale. Fig. 5 is a central vertical section, partly in elevation, of the lower rear corner of one of the brackets on the same scale as Fig. 3. Fig. 6 is a transverse section on the line $y-y$, Fig. 3, of 30 one of the extensible skeleton shelves, part of the end piece of the said shelf being broken away.

My shelves are supported mainly on two bracket-frames, which frames are preferably formed of tubing 7, cross-rods 8, and corner-pieces 9, the tubing 7 being bent into the desired form until its ends nearly meet and then connected together by extending the said ends into the sockets of the corner-piece 9, to which the said ends may be secured in any proper manner—as, for example, by pins 10, as shown 35 in Figs. 2 and 5. The corner-pieces are of a right-angular form at their back and bottom, so as to fit the angle of the window-stool 11 and wall, as shown in Fig. 2, or, if desired, the back of the corner-piece may rest on the 40 face of the casing 12 when applied to a window in which the ends of the stool 11 do not project beyond the casing. The rear side of the corner-piece may be provided with a 45 screw-hole flange, as shown in Fig. 1, if desired, and I prefer to cover the rear side and

bottom of said corner-piece with rubber, as indicated at 25, Fig. 5. Near the top and bottom of the frames I place the cross-rods 8 for the end pieces of the skeleton shelves to rest on. I so shape the frame that when the cross-rods 8 are horizontal the frame will extend obliquely upward and outward, and it should have obliquity enough to bring the rear end of the upper cross-rod in substantially the vertical plane of the front end of the lower cross-rod, so that no part of the upper shelf will be directly over any part of the lower shelf. I provide the rear edge of the frame with an eye 15, from which a chain 16 or equivalent fastening may be extended to a 55 screw-eye or fastening 13 on the window-casing 12, as shown in Fig. 2.

Each shelf is composed of four extensible bars and two end pieces 17, each end piece being provided with a rolled-over upper edge 60 18 to hook upon the shelf cross-rods 8 of the frame. The extensible bars are formed each of a hollow and flattened tube 19 and a flat strip of metal 20, fitted to and sliding within the said flattened tube. The said strips have 65 one end bent at a right angle to their bodies and are secured by rivets to one of the end pieces 17, the right-hand end piece, as shown in Fig. 1. Short pieces 21 of like strips of metal are bent into the right-angular form and have 70 one member thereof riveted to the other end piece, the upper left-hand end piece as shown in Fig. 6, while the other member of these angular pieces extends into the ends of the flattened hollow tubes 19, which are riveted there- 75 to, as shown in Fig. 3. The strips 20 and tubes 19 should be nearly of equal length; but inasmuch as a short portion of the tubes at the ends nearest the end piece is filled up by the fastening angle-piece 21 the metal strips may 80 be that much shorter than the tubes. The strips and tubes are riveted to the end pieces so as to stand up edgewise—that is, with their broad sides in the vertical position—and they are secured to the said end pieces quite a dis- 85 tance from the rolled-over suspension upper edge 18 of the said end pieces 17, as best shown in Fig. 6. Taking an end piece with the strips secured thereto and another end piece with the tubes secured thereto and inserting the 90 95 100

ends of the strips into the tubes, an extension skeleton shelf is formed, which may be shortened until the strips strike bottom in the tubes and may be lengthened by drawing out the 5 strips until only a sufficient portion is double to support the shelf, whereby the shelf may be extended or contracted in length for adjusting it to windows of any width within its range. When the two frames are properly 10 placed on the window, as described, the shelf may be adjusted lengthwise to the proper distance between the said frames and then suspended therefrom by hooking the rolled upper edge over the cross-rods, the bars of the 15 shelf and the lower part of the end pieces coming down below the cross-rods, with their ends bearing on the tubing 7 at the inside of the frame, as shown. The other shelf is adjusted and applied in the same way. It is only necessary to lay something on the top of the skeleton shelves for a surface to render the shelves 20 ready for use. I prefer to employ for this purpose the extensile trays, which are formed of two half-pans--that is, pans that are open 25 at one end the same as if cut transversely to remove one end. These pans 22 and 23 have sides and one end with rolled upper edges 24, the rolled edge of one pan being a little smaller than the other, so as to slide therein. The 30 part or pan 22 with the smaller roll is a little the larger as to its body part, so that while the roll of the pan 22 slides within the roll of the pan 23 the body of the pan 23 slides within the body of the pan 22, as shown best by the 35 front view Fig. 1. These two pans may be of

substantially the same length and may be contracted to nearly the length of only one part or extended to nearly twice that length, so that they may be adjusted to the length of the adjusted shelves and placed thereon to receive 40 the plants. As soon as the shelves are loaded with plants they will be found firm enough for all practical purposes, even though the lower ends of the frame merely rest on the top of the window-stool, as shown, and no fastening is employed except the chain and eyes at 45 the upper end of the frames.

I claim as my invention—

1. The combination of the two separate frames having shelf-supports and adapted to 50 be secured in place on the opposite sides of a window, with a plurality of extensile shelves adapted to be adjusted to the space between the said frames, and the extensile trays for resting upon the said shelves, substantially as 55 described.

2. An extensile skeleton shelf consisting of flattened tubes and strips arranged to slide one within the other and secured to the end pieces for hanging the said shelves, substantially as described.

3. The extensile trays consisting of two half-pans open at one end, with sides having the rolled upper edges, the pan-bodies and rolled edges being fitted to slide one within 60 the other, substantially as described.

GEORGE W. CURTIS.
